(57) **CLAIM**

The ornamental design for a floor lamp as shown and described.

DESCRIPTION

FIG. 1 is a perspective view of a floor lamp showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and

FIG. 9 is a partial enlarged view of portion **9** in FIG. 1;

FIG. 10 is a partial enlarged view of portion **10** in FIG. 2; and,

FIG. 11 is a perspective view of a floor lamp showing my new design, in a closed state.

The broken lines depict portions of the floor lamp and form no part of the claimed design.

The dot dash line is included for the purpose of illustrating the bounds of the enlarged view and forms no part of the claimed design.

1 Claim, 11 Drawing Sheets
